UNITED STATES PATENT OFFICE.

LELAND L. SUMMERS, OF WASHINGTON, DISTRICT OF COLUMBIA.

GUN.

1,401,010.

Specification of Letters Patent. Patented Dec. 20, 1921.

Application filed May 24, 1918. Serial No. 236,356.

To all whom it may concern:

Be it known that I, LELAND L. SUMMERS, a citizen of the United States, residing at Washington, in the District of Columbia, have invented certain new and useful Improvements in Guns, of which the following is a specification.

This invention relates to the construction of ordnance, particularly high-powered guns, 10 designed to withstand extremely heavy internal pressures. The invention contemplates the provision of means for so distributing the stresses due to the internal pressure developed at the moment of firing, as to 15 render it possible not only to utilize pressures of extremely high order of magnitude, but also to render possible the utilization in gun construction of ordinary grades of steel, including cast steel.

According to the invention the gun tube, 20 barrel or lining, hereinafter for convenience referred to as the tube, is subjected to a compressive stress due to an externally applied hydrostatic or fluid pressure, which pressure 25 is of such magnitude as to compensate, to a greater or less degree as may be desired, the internal pressure developed within the tube at the moment of firing. It is thereby rendered possible to construct a gun capable of 30 withstanding much higher internal pressures than have heretofore been considered practicable, the gun being capable therefore of operating at correspondingly high muzzle velocities and of attaining proportionately 35 longer ranges.

The principle may be applied in various ways, and is subject to various modifications according to the particular results sought. Certain of these modifications will be later 40 described. Illustrative embodiments of the invention are shown in the accompanying drawings, wherein:—

Figure 1 is a central longitudinal sectional view of one type of gun embodying my invention, parts being broken away;

Fig. 2 is a transverse section thereof on line II—II of Fig. 1;

Fig. 3 is a partial central longitudinal sectional view of a modified construction having multiple fluid-pressure chambers;

Fig. 4 is a similar view of a further modification; and

Fig. 5 is a sectional detail of a modified form of gas-cushioning chamber.

Referring to Figs. 1 and 2, 10 indicates the gun tube, provided with the usual rifling 11.

12 is the firing chamber and 13 the breech block. These several parts may be of any approved design and construction.

The tube 10 is surrounded by a jacket 14, 60 which may extend the entire length of the tube, including the firing chamber, or which may be limited to those regions in which the maximum internal pressure is developed at the moment of firing. The jacket, which 65 may in some cases be of cast steel, is provided with an internal recessed portion 15, which, when the parts are assembled, constitutes a fluid-tight annular chamber completely surrounding any desired portion of the tube 10. 70 This tube may be locally supported by any desired number of bearing lugs or projections 16, which are preferably integral with the jacket 14, the bearing surfaces of the lugs preferably conforming to the exterior 75 curvature of the tube, but the lugs being so positioned and of such dimensions as not to interrupt the continuity of the annular chamber 15.

In the particular embodiment of the invention chosen for illustration the tube 10 is externally screw-threaded at the portions indicated by 17 and 18; and the jacket, the end portions of which are provided with corresponding internal threads, is screwed into 80 position, this operation being preferably carried out while the jacket is at an elevated temperature relative to that of the tube in order to secure a shrinking fit, as is well understood in this art. As illustrated, the forward end of the jacket abuts against an integral flange or collar 19 surrounding the muzzle of the gun tube, while its rear end is encircled by a screw-threaded holding collar 20, which also engages the screw-threads 18 at 85

90 the rearward portion of the tube 10. 21 represents the usual massive external ring or band surrounding the breech of the gun. As will be obvious to those skilled in this art, the details of construction and design may be 95 widely varied according to the type of gun or the nature of the service required. It is essential that the annular chamber, which is intended for the reception of a liquid under extremely high hydrostatic pressure, should 100 be absolutely liquid-tight under every operating condition. Even the shrinking fit of the jacket may be insufficient to assure the necessary degree of tightness under all conditions, and I therefore prefer to provide an 105 absolute seal by means of an autogenous weld (arc, acetylene or the like) applied to some 110

or all of the joints. Such welds are indicated by way of example at the several lines indicated by the numerals 22.

It may be observed that in this type of construction it is not necessary to machine either the external face of the gun tube 10, or the internal face of the jacket 14, except at the contacting areas.

In explanation of the results attainable by the construction above described, let it be assumed that oil or other non-freezing liquid or solution filling the annular chamber 15 is maintained therein under extremely high pressure, which may amount for example to 20,000 pounds or upward per square inch of surface. There is thereby exerted a corresponding internally directed or compressive stress upon the gun tube, the pressure being, of course, suitably limited to avoid crushing or distorting the tube on the one hand, or disrupting or permanently deforming the surrounding jacket on the other. It will be clear that under these conditions the effective internal pressure, at the moment of firing, tending to deform or disrupt the tube, will be diminished by an amount corresponding to the external pressure exerted at the same moment through the liquid in the annular chamber. For example, if the internal stress developed in the metal at the moment of firing is 40,000 pounds per square inch, and the inwardly directed stress due to the liquid within the annular chamber is, at the same instant, 20,000 pounds, the differential stress tending to the lateral deformation of the tube will be only 20,000 pounds.

By properly adjusting the internal and external pressures, having due regard to the character and weight of metal in the component parts of the gun, it thus becomes possible to use extremely high internal pressures, with correspondingly high muzzle velocities and range, without danger of exceeding the elastic limit of the metal or the breaking stress of the gun.

Furthermore, the hydrostatic pressure of the liquid is exerted not only as a compressive stress upon the tube, but likewise, by reason of the thrust upon the end walls of the annular chamber 15, as a longitudinal tension upon the tube. In other words the tube is subjected simultaneously to a compressive stress and a tensile stress at right angles thereto. This tensile stress is exerted upon the entire cross-sectional area of the tube, and has the effect of further reducing its tendency to lateral distortion or deformation under either internally or externally applied pressures. Under these conditions the entire cross sectional area of the tube becomes active in resisting the tendency to deformation. For a given liquid pressure the amount of this tensile stress is of course proportionate to the area of the end walls of the annular chamber; and this chamber

is therefore proportioned in harmony with the general design of the gun to afford the desired effect.

To state the matter otherwise, the longitudinal tension imposed upon the fiber of the gun tube tends to utilize the outer fibers of the tube, and therefore to equalize the stresses in the gun tube due to the pressure developed in the firing chamber. Ordinarily the pressure developed in the firing chamber causes an excessive stress on the fiber of the tube adjacent the firing chamber, and this pressure on the tube is not transmitted until a certain distortion in the tube has taken place. It is therefore necessary in ordinary gun design to have a tube of high elastic limit, in order that the distortion may extend into the tube and yet not exceed at any point the elastic limit of the metal. By application of a longitudinal tension to the gun tube there is a constant tendency to equalize the stress on the fiber adjacent the firing chamber, and thus to utilize more effectively the entire cross-section of the gun tube when it is subjected to the stress of the powder pressure in the firing chamber.

The hydrostatic pressure of the liquid in the annular chamber is of course subject to changes of considerable magnitude, owing to volume changes in the liquid resulting from temperature variations; as well as to variations in the capacity of the chamber due to a like cause. These variations are to some degree compensating. In addition to the above, however, the liquid pressure is subject to rather wide variations due to the momentary reduction in the capacity of the annular chamber by deformation of the tube at the moment of firing. This latter variation may be limited by the provision of the lugs 16 as described above. I prefer, however, to provide a gas-cushion properly related to the liquid volume, one effect of such cushion being to absorb the sudden shocks or strains due to the above varying conditions, and more particularly to the reduction in the capacity of the annular chamber at the instant of firing. For this purpose I have provided a heavy-walled gas chamber 23, communicating with the annular chamber 15 by means of a duct 24. If desired the normal liquid level may lie within this chamber, as indicated at 25 in Fig. 1, the upper portion of the chamber being filled with air or other gas under pressure which corresponds of course to that of the liquid. Any suitable means may be provided for varying the capacity of this chamber, and thereby controlling the gas pressure and also the hydrostatic pressure of the liquid: for example a screw-plunger 26 may be provided, which projects into the chamber and may be retracted to compensate for expansion of the liquid due to rise of temperature, or vice versa, thereby permitting an

adjustment of the pressure to any desired value.

The gas-cushion used in the above described relation and properly proportioned in harmony with the general design of the gun, and particularly in relation to the volume of the liquid contents of the annular chamber, performs another function as follows: At the moment of firing the inner wall of the annular chamber 15, which in the construction illustrated is the gun tube 10, undergoes a certain lateral deformation, the effect of which is to reduce to a certain extent the capacity of the annular chamber. This results in driving an additional portion of the liquid into the pressure chamber 23, and to a corresponding degree further compressing the gas therein. However, since the pressure exerted by the confined gas varies inversely as its volume, the result of this movement is a momentary increase in the pressure exerted by the gas and a corresponding momentary increase in the hydrostatic pressure of the liquid upon the gun tube 10. As will be readily understood from the foregoing it is entirely possible, as a matter of design, by a proper proportioning of the several gun elements, including the capacity of the chambers and the relative volumes of gas and liquid therein, so to adjust the conditions at the moment of firing as practically to equalize the internal and external pressures upon the gun tube at this moment. This permits the tube to be constructed with thinner walls than would otherwise be the case, and leads to a material economy both in construction and repair. It also leads to the possibility of using for the gun tube or lining, metals or alloys which are better capable than steel of withstanding the extremely high temperatures developed, although their physical properties are not such as to permit their employment in ordinary gun construction.

Many structural embodiments of the principles above set forth will occur to those skilled in the art, and need not be described herein. However, the following modifications may be mentioned:

(1) In case it is desired to develop extraordinarily high pressures within the firing chamber, the gun construction may include two or any desired number of concentric, annular hydrostatic chambers, whereby the internal pressure may be gradually stepped down to a much lower outwardly-directed pressure imposed upon the outer jacket of the gun. In such case the hydrostatic pressure in the several chambers will progressively diminish from the interior outwardly. Each of such chambers will preferably be provided with its own gas-cushion regulator, operating as described above. It is apparent that by providing a number of these fluid pressure chambers, the

stress imposed upon the gun tubes can be reduced to a minimum and an excessive pressure can be carried in the firing chamber without subjecting the concentric series of tubes, each surrounded by fluid pressure, to pressures which will cause them to be distorted beyond their elastic limits; or on the other hand, tubes of moderate elastic limit may be utilized to withstand the excessive gun pressures. It will be further apparent that this construction lends itself to the designing of a gun of extreme range, since the chamber pressure may be increased to such extent as would ordinarily disrupt the strongest metal, this excessive pressure being neutralized wholly or in part by a succession of encircling hydrostatic pressure chambers, thereby enabling the final pressure on the external jacket to be absorbed by ordinary metal. A construction of this type is illustrated in Fig. 3, in which 15, 15 represent the multiple pressure chambers, 14 the external jacket, 10 the gun tube, and 10^a an intermediate tube between the annular pressure chambers. 90

(2) The principle further lends itself to the construction of sub-caliber guns.

(3) As stated above, the longitudinal tension on the gun tube varies according to the area of the end wall of the annular chamber. However, in case the jacket is quite rigid the tension imposed upon the tube may be less than is desirable. Under certain conditions, therefore, I provide a certain flexibility in the jacket in order to increase to any desired extent the longitudinal tension upon the tube. One means of accomplishing this is shown in Fig. 4, in which the forward end of the fluid-pressure chamber 15 is enlarged as indicated at 30, the corresponding portion of the jacket 14 being at the same time curved outwardly in such a manner as to impart a certain flexibility to the structure, resulting of course in increasing the longitudinal strain upon the tube. It will thus be seen that great latitude of design is afforded, whereby certain specific desirable conditions may be attained. 100

(4) The fluid contained under hydrostatic pressure in the annular chamber or chambers 15 may also be utilized to increase the rate at which the internally developed heat is dissipated into the air: for the heat developed within the tube 10 is transferred in part to the surrounding body of liquid, by which in turn, the liquid acting both conductively and by convection due to its circulation, it is transmitted to the outer jacket and thence to the air. Any special radiating means for increasing this effect may be provided. 115

(5) Instead of maintaining a pre-determined pressure in the annular chamber or chambers, as described above, I may provide 130

a fluid connection between such chamber and a suitable source of gas or liquid under pressure. For example in the modification illustrated in Fig. 5 the gas-chamber 23^a communicates by duct 24^a with the barrel or firing chamber of the gun; for example at a point at which the gaseous products of the explosion have expanded to about twice their initial volume and hence have fallen 10 to approximately one-half of their initial pressure. The chamber 15 is also in communication with the gas-chamber 23^a, for example through the annular passage 28. 29 represents a check-valve or element of 15 like function, for preventing the gas within the chamber from escaping into the barrel of the gun while permitting the gas from the barrel, at moments when excess pressure exists therein, to flow into the 20 chamber 23^a. The effect of this construction is to produce within the annular chamber or chambers 15 a pressure which may bear any desired ratio to the pressures existing in the firing chamber at the moment of firing, 25 up to the full value of such pressures, utilizing a portion of the spent gases, at suitable pressure and temperature, to transmit added pressure to the interspace 15. A further advantage is that this pressure is renewed 30 at each discharge of the gun, thereby compensating for loss of pressure by slow leakage or other causes. Obviously the presence of liquid in the annular chamber is not essential, the direct gas pressure being equally 35 effective. Obviously also the fluid pressure might be derived from any other suitable source.

In case the fluid pressure is derived wholly or in part from the explosive gases, it may 40 be desirable to build up this pressure gradually, if necessary by the firing of one or more preliminary partial charges.

My invention is not limited to the use of liquid within the annular chamber or chambers as a means for exerting the desired inwardly directed pressure upon the gun tube, or tubes, inasmuch as I may employ for this purpose gases under pressure, including gases liquefiable under the existing conditions, or even finely divided and highly mobile solids, such as graphite, which are quite capable when confined of effectively transmitting applied pressures. The expression "fluid medium" employed in the claims is

intended to include all mobile substances 55 capable of accomplishing the purpose herein set forth.

I claim:

1. In a gun, the combination with a tube and an enveloping member spaced therefrom but united therewith at opposite ends to provide a closed annular interspace, said interspace enlarged at one end, whereby the gun-tube may be maintained under longitudinal tension by hydrostatic pressure within 60 the interspace.

2. In a gun, the combination with a tube and an enveloping member spaced therefrom but united therewith at opposite ends to provide a closed annular interspace, said 70 interspace enlarged at one end, whereby the gun-tube may be maintained under longitudinal tension by hydrostatic pressure within the interspace, and means for varying the effective capacity of said interspace and 75 thereby adjusting the hydrostatic pressure of fluid therein.

3. In a gun, the combination with a tube and an enveloping member spaced therefrom but united therewith at opposite ends 80 to provide a closed interspace, of a fluid under maintained hydraulic pressure in said interspace, and means for transmitting to said fluid added pressure from the interior of the gun at the moment of firing.

4. In a gun, the combination with a tube and an enveloping member spaced therefrom but united therewith at opposite ends to provide a closed interspace, of a fluid under maintained hydraulic pressure in said 90 interspace, means for varying the effective capacity of said interspace and thereby adjusting the hydrostatic pressure of fluid therein, and means for transmitting to said fluid added pressure from the interior of the gun at the moment of firing.

5. In a gun, the combination with a tube and an enveloping member spaced therefrom but united therewith at opposite ends to provide a closed interspace, of a duct between the interior of the gun and said interspace and a check valve for maintaining a fluid under hydraulic pressure in the interspace and allowing gases from the interior of the gun to pass into the interspace.

In testimony whereof I affix my signature.

LELAND L. SUMMERS.
